US00D952023S

(12) **United States Design Patent** (10) **Patent No.:** **US D952,023 S**
(45) **Date of Patent:** **** May 17, 2022**

(54) **HANDHELD IMAGING DEVICE**

(71) Applicant: **MolecuLight Inc.**, Toronto (CA)

(72) Inventors: **Ralph S. Dacosta**, Etobicoke (CA); **Simon Treadwell**, Toronto (CA); **Todd Daynes**, Aurora (CA); **Todd Meaney**, Thornhill (CA); **Danielle Dunham**, Toronto (CA); **Carl Annis**, Oakville (CA); **Connor Wright**, Toronto (CA); **Kimberlyn Dampitan**, Mississauga (CA); **Nitesh Mistry**, Toronto (CA)

(73) Assignee: **MOLECULIGHT, LTD.**, Toronto (CA)

(**) Term: **15 Years**

(21) Appl. No.: **29/762,417**

(22) Filed: **Dec. 16, 2020**

(57) **CLAIM**

The ornamental design for a handheld imaging device, as shown and described.

DESCRIPTION

FIG. 1 is a top, front and right side perspective view of a handheld imaging device showing our new design.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines depict portions of the handheld imaging device in which the design is embodied that form no part of the claimed design.
